(57) **CLAIM**

I claim, the ornamental design for a male latch of buckle, as shown and described.

DESCRIPTION

FIG. 1 is a top and front perspective view of a male latch of buckle, showing my new design;

FIG. 2 is a front elevation view thereof;

FIG. 3 is a rear elevation view thereof;

FIG. 4 is a left side elevation view thereof;

FIG. 5 is a cross-sectional view of the male latch of buckle when viewed from the right side thereof;

FIG. 6 is a top plan view thereof; and,

FIG. 7 is a bottom plan view thereof.

The broken lines shown in the above FIGURES are for illustrative purposes only and form no part of the claimed design.
